UNITED STATES PATENT OFFICE.

DAVID COHEN, OF NEW YORK, N. Y.

DESIGN FOR A DISPLAY ADVERTISING-VEHICLE.

49,641.

Specification for Design.

Patented Sept. 12, 1916.

Application filed January 19, 1916. Serial No. 73,080. Term of patent $3\frac{1}{2}$ years.

To all whom it may concern:

Be it known that I, DAVID COHEN, residing at New York, county and State of New York, have invented a certain new, original, and ornamental Design for a Display Advertising-Vehicle, of which the following is a specification, reference being had to the accompanying drawing, forming part thereof.

The figure is a perspective view illustrating the new design.

The new design comprises a wheeled vehicle made up so as to include a driver's seat and a platform behind the seat. The platform is inclosed by ornamental walls mostly of glass and is covered by an ornamental roof with small windows or ventilators therein. The walls are designed and ornamented so as to give the appearance of a show window when viewed from without.

I claim:

The ornamental design for a display advertising vehicle, as shown and described.

DAVID COHEN.
